CASING FOR THE MOTORS AND SPINNING
POTS OF TEXTILE SPINNING MACHINES

Walter Hartley, Radcliffe, England

Application February 25, 1950, Serial No. 146,260
In Great Britain March 9, 1949

4 Claims. (Cl. 57—76)

1

This invention has reference to casings for the motors and spinning pots of textile spinning machines and has for its object to provide improvements in the construction and mounting thereof whereby a casing can be provided which is made in separate parts and thereby permits heavy acid-proof material to be used in the construction without making any part unduly heavy to handle.

According to this invention a casing for a motor and spinning pot for a textile spinning machine comprises a casing surrounding the motor, and detachably secured to the base supporting the motor, the casing being outwardly flanged at the top and having under the flange a resilient support adapted to rest on a support on the frame of the machine and around an opening through which the motor and casing is lowered into position, the flange having on the top a resilient support forming on the outside a liquid seal with the support below the flange and internally constituting a buffer for the motor casing and also constituting a cushion for a detachable cover which also forms the bottom of the top part, the cover having upward and downward flanges, the downward flange enclosing the outside faces of the seal and the upward flange embracing the bottom end of a detachable top part of the casing, and constituting one wall of a drainage channel, an opening being provided into a box-like extension carrying a detachable hollow drainage plug, the top part of the casing surrounding the spinning pot and resting in the upward flange and having a liquid seal groove at the top for the flange of a lid and being detachable from the detachable cover so that the pot can at any time be completely exposed, aligning devices being provided to ensure that the drainage plug will always be in its correct position with regard to a drainage channel on the machine.

The invention is more particularly set forth with reference to the accompanying drawing which shows in sectional elevation one construction of a casing made according to the invention and for use on a machine for spinning artificial silk.

The casing is made in three main parts, two being circular and referred to herein for convenience as the top part 1 and the bottom part 2, and the other being between the two and serving as a cover for the bottom part 2 and as a bottom for the top part 1.

The bottom part 2 which encloses the motor 3 for rotating the spinning pot 4 is mounted on or secured to a bottom attachment plate 5 sup-

2

porting the motor 3 and on which it is supported by resilient mountings 6. The top part 1 surrounds the spinning pot 4 and mounted on the bottom part 2 between it and the top part 1 is a cover 7 which as well as serving as a cover for the bottom part 2 serves as the bottom of the top part 1 which rests on it.

The bottom part 2 is made with its top edge outwardly flanged at 8 and under the flange is 10 or are a resilient support or supports 9 which may be continuous or non-continuous and made of a resilient material or construction e. g. a rubber or like ring. This resilient supports rests on a further support 10 on the spindle rail 11 of the machine in an opening of which spindle rail, the casing and motor are hung. This support 10 is conveniently in the form of a ring and may be made of rubber or like material or it may be of metal such as an alloy containing lead which can be burned or welded on to the lead covering of the spindle rail 11. Above the flange 8 and embracing it, and also projecting inside the bottom part is a further resilient member or members 12 which, with members 9 and 10 will provide a complete seal to prevent the entrance of acids or other liquids that may be on the machine. If desired, and as shown in the drawings, supports 9 and 12 may be made in one with each other and slotted to allow the flange 8 to be embedded therein. The part of the resilient member or members 12 within the casing will act as a buffer to the flange of the casing of the motor 3.

Resting on the support 12 above the flange 8 is the part 7 which constitutes a bottom for the top part 1 and a cover for the bottom part 2. This part 7 has a downward flange 13 enclosing the resilient supporting and sealing means 8, 10 and 12 and has an upward flange 14 to surround 40 and act as a socket for the lower end of the top part 1 which thus stands detachably on the part 7 and yet firmly held by the flange 14.

The part 7 rises toward the centre where a hole is provided so that the part can be passed 45 over the spindle 15 of the motor 3, and from this centre the part 7 is downwardly inclined to the upward flange 14 which thus forms one face of a channel into which any liquid will drain.

At one place in this flange 14 a hole is provided 50 on the outside of which and attached to the flange is a box-like extension 16 having holes in the top and bottom into which holes a hollow drainage plug 17 is passed from the top, a flange on the top end of the plug holding it in place, 55 the plug having openings in its wall to allow

liquid to drain through and fall into a drainage channel 18 on the machine from which the drainage is carried away by any suitable means.

The top part 1 is conveniently made of chemically pure lead and is thus acid proof, and as already stated stands inside the upturned flange 14 of the part 7, and is easily detached therefrom and has an opening to coincide with box-like drainage extension 16 so that any liquid on the part 1 can easily drain away to the plug 17. The top part 1 is circular and surrounds the spinning pot 4 which is rotated by the spindle 15 of the motor 3, through the mantle 19 provided with aligning pegs 20 and is connected to the spindle 15. On the top of the top part 1 is a groove 21 which forms a water seal with the lid 22. If there should be any difficulty in mounting or removing the spinning pot 4 the top part 1 can easily be lifted off so that there is easy access to the spinning pot and its mounting. This top part though it may be made of metal such as chemically pure lead which is heavy, is, owing to its detachability from the cover, not of any great weight and consequently it can easily be lifted on and off.

In order to ensure the correct aligning of the drainage plug 17 with the drainage channel 18, lugs, not shown in the drawing are provided on the top part 1, the bottom part 2 and the intermediate part or cover 7 and these when aligned will ensure that the drainage plug 17 is in its correct position.

It will be appreciated that the resilient supports as well as acting as a seal and buffer also act as cushions and prevent hammering of the parts under any vibration which may occur in the machine when running.

I claim:

1. In a textile spinning machine having a motor, and a spinning pot disposed above said motor and connected therewith for rotation thereby, the combination of a housing comprising a cylindrical casing enclosing the motor, a removable cylindrical casing enclosing the spinning pot, an intermediate member disposed between said casings and forming a cover for the motor casing

45

and a bottom for the spinning pot casing, said intermediate member being constructed to form a drainage channel in the lower part of the spinning pot casing and having an outlet in communication with said drainage channel, resilient supporting means disposed between said intermediate member and the upper end of the motor casing, and a removable cover disposed on the upper end of said spinning pot casing.

10 2. In a textile spinning machine, the combination set forth in claim 1, said motor casing having a bottom plate secured therein and said motor flexibly supported on said bottom plate.

15 3. In a textile spinning machine, the combination set forth in claim 1, characterized by an upwardly extending peripheral flange carried by said intermediate member and forming a seat for the lower end of the spinning pot casing.

4. In a textile spinning machine having a motor, and a spinning pot disposed above said motor and connected therewith for rotation thereby, the combination of a housing comprising a cylindrical casing enclosing the motor, a removable cylindrical casing enclosing the spinning pot, an intermediate member disposed between said casings and forming a cover for the motor casing and a bottom for the spinning pot casing, said intermediate member being constructed to form a drainage channel in the lower part of the spinning pot casing and having an outlet in communication with said drainage channel, resilient supporting means disposed between said intermediate member and the upper end of the motor casing, a removable cover disposed on the upper end of said spinning pot casing, a bottom plate secured in said motor casing and flexibly supporting said motor, a laterally extending peripheral flange carried at the upper end of the motor casing, and a downwardly extending peripheral flange carried by the intermediate member in encircling relation to the flange of said motor casing.

WALTER HARTLEY.
